US00D598945S

(12) **United States Design Patent**
Gillespie

(10) **Patent No.:** **US D598,945 S**
(45) **Date of Patent:** **** Aug. 25, 2009**

(54) **PROJECTOR MOUNTING SYSTEM**

(75) Inventor: **John Michael Gillespie**, Green Oaks, IL (US)

(73) Assignee: **Peerless Industries, Inc.**, Melrose Park, IL (US)

(**) Term: **14 Years**

(21) Appl. No.: **29/322,954**

(22) Filed: **Aug. 14, 2008**

(51) **LOC (9) Cl.** **16-02**

(52) **U.S. Cl.** **D16/235**

(58) **Field of Classification Search** D16/235, D16/242, 244-245; 248/917, 519, 920, 279.1, 248/317, 324, 344, 346.06, 523, 278.1; D8/349, D8/354-355; 352/243

See application file for complete search history.

(57) **CLAIM**

The ornamental design for a projector mounting system, as shown and described.

DESCRIPTION

FIG. 1 is a perspective view of the projector mounting system showing my new design;

FIG. 2 is a front view thereof;

FIG. 3 is a left side view thereof;

FIG. 4 is a top view thereof;

FIG. 5 is a bottom view thereof;

FIG. 6 is a back view thereof;

FIG. 7 is a right side view thereof;

FIG. 8 is a perspective view of another embodiment of the projector mounting system showing my new design;

FIG. 9 is a back view of the projector mounting system in FIG. 8;

FIG. 10 is a left side view of the projector mounting system in FIG. 8;

FIG. 11 is a top view of the projector mounting system in FIG. 8;

FIG. 12 is a bottom view of the projector mounting system in FIG. 8;

FIG. 13 is a back view of the projector mounting system in FIG. 8; and,

FIG. 14 is a right side view of the projector mounting system in FIG. 8.

The broken lines shown are for illustrative purposes only and form no part of the claimed design.
